PRESSING MECHANISM

Edward P. Holder, New York, N. Y., assignor to
 American Machine and Metals, Inc., New York,
 N. Y., a corporation of Delaware

Application January 7, 1937, Serial No. 119,396

17 Claims. (Cl. 38—4)

The invention relates to new and useful improvements in power-operated presses, and more especially to such presses as are especially adapted and capacitated, among other uses, for pressing garments and the like.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a front elevation of a press embodying the invention;

Fig. 2 is a side elevation looking at Fig. 1 from the left;

Fig. 3 is a view corresponding to Fig. 2, with most of the frame and other parts omitted, and showing the fluid pressure actuating and control mechanism partially diagrammatically for the sake of clearness;

Fig. 4 is a top plan showing two of the presses positioned and connected together for synchronous operation by a single attendant;

Fig. 5 is a diagrammatic elevation of the interconnected actuating means and controls for the two presses shown in Fig. 4, with certain of the parts in different positions from those occupied in the press, for sake of clearness in showing the controls;

Fig. 6 is a diagrammatic detail of a form of control valve for the pressing mechanism;

Fig. 7 is a fragmentary detail of automatic timing means of the pressing mechanism; and

Fig. 8 is a sectional detail taken on the line 8—8 of Fig. 1.

Objects of the invention are to provide a very strong, compact, powerful, convenient and speedy press, and to this end, among other things, a press has been provided having an especially strong frame in proportion to the metal used, and which is designed for straight-line application and absorption of the main stresses; a frame disposed essentially at the back of the machine, with all the working parts in the front of the machine and accessible in the fullest de-

gree; to provide for applying the ironing pressure in straight lines between supports or mountings for the pressing members mounted directly upon the frame, and to avoid leverage systems together with the inaccuracies and unbalanced strains incident thereto; to provide a pressing station and work supply and delivery station which are relatively far apart, whereby the operator is relatively remote from the pressing station, is protected from the heat thereof, and has enhanced safety from hurts and burns in that the pressing station is normally out of reach and no work at the pressing station is required of the operator; to provide a machine whereat the operator may work efficiently either standing or sitting with full freedom to change position as desired; to provide pressing members which are in tilted position, thereby affording simple and efficient drainage, and presenting the work support in favorable position before the operator for handling and arranging the work, and also providing lighting unshaded and unobscured by the mechanism; to permit full use of the hands of the operator in handling the work and at the same time, as a safety feature, effecting the pressing out of the reach of the operator; to provide absolute predetermined pressure on the work, irrespective of thickness of the work or shrinkage of pads, and eliminating the lost movement and uncertainties of lever systems; to provide for easy and rapid handling of the work by presenting the work carried at convenient distance and in convenient position before an operator either sitting or standing; to provide for double interconnected, alternately-operating pressing mechanisms having the advantages outlined, and which may be attended and controlled by an operator at a single fixed station; and also to provide other features and advantages which will be set forth hereinafter in connection with the detail description of the present preferred embodiment.

Referring now to the embodiment of the invention illustrated by way of example in the accompanying drawings, a vertically disposed frame 1 is shown, having a base 2, the frame being preferably of integral sheet material, as for instance welded sheet steel. The vertically disposed part of the frame constitutes the back of the machine, and is preferably box-like and internally hollow, thereby affording support and housing for the actuating and controlling means. The upper portion 4 of the frame is curved forwardly to constitute an overhang from which is supported the upper part of the pressing mechanism, and a

straight-line mounting is provided for the pressing mechanism between the head 4 and the base 2 of the frame. The front of the machine is entirely open and the pressing mechanism is mounted at the front of the machine.

In accordance with one feature of the invention, one member of the pressing couple is movable laterally to and fro between a work pressing position and a work receiving and delivering position, which latter position is directly in front of the operator and at a substantial distance from the pressing station. After the operator has positioned the work, it is carried from the operator's station to the pressing station, and after pressing it is returned to the operator's station by the movement of this part of the machine.

As embodied, one of the pressing members, such as the pressing head 11, is mounted or suspended from the head portion 4 of the frame in a forwardly and outwardly inclined position, and the other member of the pressing couple, such as the buck 12, is mounted to swing on a pivotal support, inwardly into pressing position in alignment with the pressing head (solid lines, Fig. 2) and outwardly away from the pressing position, past its vertical center, into an outwardly and downwardly inclined work delivering and receiving position (shown in dotted lines in Fig. 2). As shown, the pressing buck 12 is mounted upon a support 13, which at its bottom end has downwardly-projecting, apertured lugs 14, which are pivotally supported upon a shaft 15, which is mounted in brackets 16 and 17, fixed to and extending upwardly from the base 2 of the frame. The work support thus has an ample pivotal bearing directly on the machine frame and directly in the line of thrust of the press, and the cooperating presser head is stationary except for the free, straight-line movement to effect the work pressure between the head and the buck. The members 11 and 12 of the pressing couple are disposed in inclined position for the pressing action, the entire structure being inclined inwardly and upwardly between the base 2 and the head 4 of the frame, and the ironing pressure is exerted only in the direct longitudinal line of the parts, and also is exerted directly on the presser members, without the use of levers or like mechanisms.

The buck 12 and its pivotally mounted support 13, after the pressing is completed, are caused to swing outwardly from the full line position to the dotted line position of Fig. 2. In this dotted line position, the buck is inclined forwardly and downwardly directly in front of the operator in the most favorable position for rapid and efficient removal of the finished work and for like loading of new work on to the buck. The work is thus presented directly to the operator at a fixed station, who may be sitting or standing, and the forwardly inclined position of the buck is most favorable to rapid and efficient handling of the work. The upwardly and outwardly inclined support permits space for the operator's feet beneath the support in the open position, so that the work is brought within easy and efficient reach of the operator, in a seated position. The inclined positions of the presser members also give very effective drainage of condensed steam from the heating system. A table 18 may be provided on the support 13 if desired.

Referring now to the embodied form of means for actuating the traveling buck and its support (Figs. 2, 3 and 5), it is designed to be operated by pressure fluid, such as compressed air, and in

said form a cylinder 21 is pivotally supported at 22 upon the frame 1 of the machine. The cylinder has a double-acting piston, and its piston rod 23 is pivoted at 24 to the supporting pedestal 13 of the work carrier. The fluid pressure is applied alternately at the two ends of the cylinder 21 to swing the carrier to and fro between the pressing position and the work-receiving and delivering position at the will of the operator. The mechanism for operating and controlling a single press is shown especially in Figs. 2 and 3, and will be first described, and as embodied the compressed air is brought from a suitable source by a pipe 27, which communicates by a short pipe 28 with a valve 29. Valve 29 is connected to the right-hand end of cylinder 21 to apply the air pressure to swing the pedestal 13 from the work-receiving position, shown in dotted lines in Fig. 2, to the work pressing position, shown in solid lines in Fig. 2.

A pipe 32 connects with the valve 29 and by a flexible pipe 33, which opens into the right-hand end of the pivoted cylinder 21. The valve 29 is constructed to normally connect its end of cylinder 21 to the atmosphere while cutting off the pressure from pipe 27, and is then in the position of the valve 29^a in Fig. 5. Pedal-operated means are preferably provided whereby the operator actuates valve 29 to swing the work pedestal from the dotted line to the full line position of Fig. 2, and as embodied a spring-pressed foot pedal 31 is pivoted at 38 upon the machine frame, and has a downwardly-extending arm 39 adapted to contact with the end of the valve stem 40 of valve 29, which projects from the valve casing. The stem 40 of valve 29 (Fig. 5) has fixed thereon two valve discs 45 and 46, which are located in valve chambers 43 and 44, respectively. There is an air port 47 communicating between the two chambers, and a spring 48 urges the valve 45 onto its seat to normally shut off the pressure from the pipe 27, and the spring holds valve disc 46 open, and pipe 32 and chamber 44, and the right-hand end of cylinder 21, are normally in communication with the atmosphere.

When the pedal 31 is depressed, valve stem 40 is moved against its spring 48, valve disc 46 is closed, and disc 45 is opened against the spring, and the air pressure from pipe 27 passes through pipe 32 into cylinder 21 and moves the piston to the left, and swings the pedestal 13 from the dotted-line work-receiving position to the full-line pressing position in Fig. 2. The pedestal comes to rest against a suitable stop, with the pressing buck 12 in alignment with the pressing head 11 and is held in that position by gravity, and the air pressure is cut off from cylinder 21 by the operator releasing the pedal 31, which cuts off the air pipe 27 from the cylinder, and relieves the cylinder and pipe 32 into the atmosphere.

There is provided by one feature of the invention a presser head mounted directly upon the machine frame, and having no other necessary movement except the relatively short, straight-line movement required for exerting the pressure upon the work, and this movement is of variable extent, automatically accommodating itself to variations in thickness of the work or of the padding, and thus the full predetermined pressure is exerted on the work under these varying conditions. As embodied, the fluid pressure operates directly upon the presser head at a plurality of longitudinally spaced-apart points with floating pressure, which insures uniform

pressure throughout the work, applied directly, and without the intervention of levers or other connections. As embodied, the elongated presser head 11 has projecting from the upper face thereof transversely-disposed pairs of upwardly projecting rods 54, 55 and 56, 57, the respective pairs being spaced apart along the head. These rods are resiliently supported thereby to hold the presser head 11 yieldingly away from the pressing position, while allowing the air pressure to act directly upon the head 11 at these spaced-apart points to press the head against the work. As embodied, two diaphragm chambers 58 and 59 are fixed at 60 and 61 to the head 4 of the machine frame and extend downwardly therefrom. The diaphragm casings 58 and 59 have, respectively, downwardly-extending cylindrical portions 62 and 63, which terminate in transversely disposed plates 64 and 65.

20 The pairs of rods 54, 55 and 56, 57, which extend upwardly from the back of the presser head 11 project through openings in these plates 64 and 65, respectively, and coil springs 69 and 70 rest on the upper faces of the plates 64 and 65 and are in compression between the plates and nuts 71 and 72, screwthreaded onto the upper ends of the rods, the presser head 11 thereby being supported resiliently away from the work position.

30 In the embodied means whereby the fluid pressure moves the presser head 11 against the action of the springs 69 and 70 and presses it against the work on the buck 12, there is mounted in each of the cylinders 58 and 59 a diaphragm 76, and 35 within said cylinders and on the under side of diaphragm 76 is a loose piston 77, having a central boss 78 to which is fixed a rod 79. The rods 79 project downwardly, respectively, through the hollow cylindrical extension 62 or 63, and these 40 rods 79 have rounded outer ends that fit into cup-like sockets in the back of the presser head 11. The fluid pressure is admitted to each of the cylinders 58 and 59, and the pressure is thus applied independently at two spaced-apart points 45 along the resiliently-supported presser head 11, thereby causing the pressure to be applied conformably and with equal force to all parts of the work.

50 Means are provided whereby the ironing pressure against the work is initiated and maintained automatically when the work support reaches the pressing position, and is then maintained automatically, either for a predetermined time or at the will of the operator. In said embodied form, a valve mechanism is provided which is actuated by the pedestal 13 coming to rest in the pressing position, the valve mechanism turning the air pressure into both diaphragm cylinders 58 and 59, the pressure thereafter being maintained on the work, either until the operator is ready to move the pedestal to delivery position, or after a predetermined time period, as hereinafter described. In the embodied form of valve mechanism, which is shown of somewhat diagrammatic form for the sake of clearness (Fig. 5), a contact lug 89 on the pedestal 13 engages with the stem 90 of a double-disc valve mechanism 91 when in the pressing position, as shown in Fig. 3, and at the left in Fig. 5.

70 Valve 91 receives the compressed air from a pipe 92, which branches off from pipe 32. The valve is normally held with its disc 94 seated and its disc 95 open by a compression spring 96. The valve has a central port 97 communicating by a pipe 98 with a cylinder 99 in which works a pis-

ton 100. The piston 100 has a short piston rod which bears on one end of a lever 101, which is pivotally supported at 102. On the opposite side of its same end lever 101 bears on the valve stem 104 of a double-disc valve 105 similar to the valves already described. Valve 105 is normally held by a spring 106 with its lowermost disc seated, thereby to shut off the fluid pressure from the cylinders 58 and 59. The valve mechanism comprises also, as a holding device for valve 105, a cylinder 109 in which works a piston 110, having a short piston rod which bears against the under side of lever 101 at its opposite end. A pressure supply pipe 111 communicates from the pipe 27 to the chamber of valve 105. A pipe 112 leads from valve 105 and supplies the fluid pressure concurrently to both of the actuating cylinders 58 and 59 of the header 11. A pipe 113 communicates from the cylinder 109 to release the pressure in cylinders 58 and 59 and to permit the springs 69 and 70 to lift the pressing head 11 from the work after the pressing is done.

The manner of operation of this valve mechanism is as follows: When lug 89 moves valve stem 90 against spring 96, the fluid pressure from pipe 32 is admitted into cylinder 99, and piston 100 is moved downwardly, and thereby opens valve 105 against the pressure of its spring 106, and the fluid pressure passes from pipe 111 through pipe 112 into each of the cylinders 58 and 59, onto the diaphragms 76 and their pistons 77, forcing the presser head 11 upon the work carried on the buck 12, and at the same time compressing the springs 69 and 70. Concurrently the pressure fluid enters cylinder 109 forcing piston 110 upwardly, and lever 101 is thus held in open-valve position by the air pressure under piston 110, and with the fluid pressure maintained on the presser head 11. This pressure will be maintained until relief of the cylinder 109, either by a relief mechanism operated by the operator in actuating the mechanism for swinging the support 13 back to the work-delivery position, or by the operation of a time mechanism. Any known or suitable means may be employed, if necessary or desirable, for effecting the timing of the parts so that the pressing action will not begin until the work support is in position. Also, any suitable means may be employed for heating the pressing members 11 and 12.

50 Referring now to the embodied means for moving the work support back to delivery position in front of the operator, a valve mechanism 116, which may be the same or similar to the valve mechanism 29, is connected by a pressure supply pipe 117 with the pipe 27. This valve, as stated, is of the same double disc type and is spring-held to shut off the fluid pressure from cylinder 21. A spring-pressed pedal 120 is pivotally mounted at 121 upon the machine, and has an arm 122 engaging with a longitudinally-slidable rod 123, which when the pedal 120 is actuated against its spring engages the stem 124 of the valve 116 to open it against its spring. A pipe 125 communicates between the valve 116 and the opposite end of cylinder 21 by means of the flexible hose 126. When pedal 120 opens valve 116, the fluid pressure is admitted to the left-hand end of cylinder 21 (Fig. 3), and the work support 13 is swung from the pressing position 70 to the work delivery position, which latter is shown in dotted lines in Fig. 2. The work support 13 need be moved only over its vertical center by the cylinder 21, and then will move by gravity and come to rest in the work-delivery position 75.

against a suitable stop, not shown, and the pressure in the cylinder 21 can be immediately relieved.

The embodied means for moving the presser head 11 away from the work, preparatory to this return movement of the work support, comprises a device for relieving the pressure on the piston 110, which is operated by the pedal 120, the parts being so timed that the head 11 is free from the work before the return movement begins. As embodied, a relief valve 127 is provided for the pipe 113, and this valve is actuated by a lever 128, which straddles the rod 123, and in engagement with a collar 129 fixed on the rod, and when lever 120 is depressed lever 128 is moved to open valve 127 to release the pressure. Thereupon piston 110 drops, and spring 106 closes the valve 105, and the pressure in pipe 112 is relieved through pipe 113 and valve 127, and springs 69 and 70 act to lift the presser head 11.

In accordance with one feature of the invention, two pressing mechanisms are interconnected to be served by one operator from a single work position or station, means being provided whereby the operator serves and controls both pressing mechanisms and operates them concurrently in reverse directions. Thus after the work is put on one pressing mechanism, the work support moves to the pressing position and concurrently therewith the work support of the other pressing mechanism moves in the opposite direction, and brings the pressed work in position before the operator to be taken off and for new work to be placed on the support. Thereupon the mechanism is again operated to carry the new placed work to the pressing position, and to move the pressed work on the other pressing mechanism into position before the operator ready to be taken off. This machine is shown in plan in Fig. 4 with the two mechanisms arranged at right-angles to each other, the operator's position being indicated by 133. It will be noted that the work supports in the open position occupy in part the same space, due to both machines delivering the work in front of the operator, but there is no mechanical interference for the reason that one support is moving toward pressing position while the other support is moving toward delivery position.

The interconnections whereby the two machines are operated in synchronism are shown diagrammatically in Fig. 5, and in many respects they are the same as the actuating and controlling mechanism for the single machine already described, and only the differences in arrangement need be further explained. The main differences are that the mechanism on one machine for lifting presser head 11 away from the pressed work, and for moving the work support back to delivery position before the operator, is here controlled automatically by the mechanism on the other machine which the operator actuates to carry the work to the pressing position. Thus when the operator has completed the work on one mechanism, and starts the work toward pressing position, this automatically carries the pressed work on the other machine away from the pressing position and places it before the operator, ready to be taken off.

In this double machine, therefore, the valve 29 on either machine, which moves the work support to pressing position, is also connected through pipe 32 to pipe 125^a, which supplies fluid pressure to the opposite end of cylinder 21^a of the other machine. The valve 29, when actu-

ated, thereby moves its own work support to pressing position, and at the same time supplies fluid pressure through pipe 125^a into cylinder 21^a of the other machine, and moves the work support of that machine from the pressing position to the delivery position in front of the operator. In like manner the preliminary retraction of the presser head 11^a from the work is effected by connecting the relief pipe 113^a and valve 127^a to be actuated concurrently with the opening of valve 29. For this purpose the relief valve 127^a is connected to be operated by a longitudinally slideable rod 135, which in this instance is interposed between the actuating lug 39 of the foot lever 37 and the stem 40 of valve 29, and thereby the one pedal is employed to operate in unison the mechanism for moving the work support of one machine to pressing position and the work support of the other machine to the work-delivering position.

In accordance with one feature of the invention, means are provided whereby the pressure upon the work may be terminated after a settable or predetermined time, so as to guard against overheating of the work or of the presser pads. This mechanism is arranged to release the pressure off the work independently of the operation of the lifting mechanism, previously described, which operates automatically when the operator moves the work support back to delivery position. This mechanism has one of its main uses in guarding against overheating in one of the presser mechanisms of the double machine in case the operator is delayed in arranging the work on one machine and starting the return movement, although it will operate equally well on a single machine. As embodied (Fig. 7), a rod 140 is pivoted at 141 to the swingable work-supporting pedestal 13, the rod being pivoted at its other end 142 to a bell crank lever 143 pivotally supported at 144 upon the frame 1. The other arm of bell crank lever 142 straddles a longitudinally-movable rod 145, and bears against a collar 146. Rod 145 is reciprocable in a guide 147 and is pivoted at its other end 148 to the piston of a dash pot timer 149 having a small port p near its lower end and beneath the piston. A relief valve 156 which is part of time mechanism 150 (Fig. 5) is connected by a pipe 151 to the relief pipe 113^a, and has an actuating lever 152 in the path of a collar 153 fixed on rod 145. When the press is opened, lever 143 is swung to the dotted line position and lifts rod 145 by means of collar 146. When the press is closed, and the pressure is automatically applied to head 11, lever 143 swings back to the full line position of Fig. 7. However, the dash pot maintains rod 145 in the elevated position, and it moves down only very slowly under control of dash pot 149, the dash pot emitting the air beneath its piston sufficiently slowly to effect the desired time delay in easing the ironing pressure. After the predetermined time, rod 145 has moved downwardly sufficiently for collar 153 to engage the valve tripping lever 152, and valve 156 relieves the pressure in pipe 112 and springs 69 and 70 lift the presser head 11, which thus occurs after the predetermined lapse of time allowed for the pressing.

A different form of valve mechanism for holding the presser head pressure on the work and for releasing it is shown in Fig. 6. In this form a double-disc, spring-pressed valve 153, of the type previously described, is interposed between the constant pressure pipe 111 and the pipe 112 which supplies the fluid pressure to the cylinders 75

58 and 59 and from them to presser head 11. The pipe 92 to which pressure is admitted by the valve 29, communicates with a cylinder 154, having a piston 155 which is impelled toward the top of the cylinder by a spring 156. The piston rod of piston 155 carries at its end an interponent 157. A bell-crank lever 159 is pivoted at 160, and one end of the lever is adapted to coact with the valve stem of valve 153, the other end of bell-crank lever 159 coacts with the piston rod 162 of a piston 163, which works in a cylinder 164, which acts as a holding device for valve 153. A pipe 165 communicates between valve 153 and the lower end of cylinder 154, and the relief pipe 113 opens out of the bottom end of the cylinder. When the valve 29 is opened by the operator, to bring the work support to pressing position, the pressure in pipe 92 moves piston 155 against its spring and moves interponent 157 into position to be engaged by lug 89 when the work support comes to pressing position. This rocks bell-crank lever 159 and admits the fluid pressure from pipe 111 into pipe 112 and puts the pressure on the head 11. When the operator releases valve 29 after the work support has swung over its center, spring 156 retracts interponent 157, so that lug 89 no longer holds valve 153 open. However, when valve 153 is opened, the fluid pressure entered the bottom of cylinder 164, forcing piston 163 upwardly, and piston rod 162 continues to hold valve 153 open through bell-crank lever 159. Valve 153 will be held open, and thus maintain the pressure on head 11, until the pressure is relieved in pipe 113, at which time the spring in valve 153 will move the valve to cut off the pressure from head 11 and relieve pipe 112 into pipe 113, thereby permitting the springs 69 and 70 to lift the presser head 11.

The invention in its broader aspects is not limited to the specific mechanisms shown and described but departures may be made therefrom within the scope of the accompanying claims without departing from the principles of the invention and without sacrificing its chief advantages.

What I claim is:

1. An ironing machine including in combination a pressing head, a pressing buck, a pivotal mounting for the buck, means for swinging the buck about its pivotal mounting between a work receiving and delivering position and a pressing position and means for moving the head toward the buck to press the work, said movement being in a radial direction with relation to the pivotal mounting of the buck.
2. An ironing machine including in combination a pressing head, a pressing buck pivotally mounted to swing between a work receiving and delivering position and a work pressing position, said positions being on opposite sides of the vertical passing through the pivot plane, and means for moving said head and pressing it against the work.
3. An ironing machine including in combination a base, a pressing head movable to and from pressing position, a pressing buck pivotally mounted on said base, and movable in a vertical plane about said pivotal mounting between a work receiving position and a work pressing position, and power and control means for moving said head toward the buck to press the work.
4. An ironing machine including in combination a pressing head, a pressing buck movable in a vertical plane between pressing relation with said head and an inclined work-receiving

position in front of the operator, and means operated by the buck reaching the pressing position for exerting pressure between the buck and head.

5. An ironing machine including in combination a pressing head movable to and from pressing position, a pressing buck movable between pressing relation with said head and an inclined work-receiving position in front of the operator, and power and control means including a valve 10 actuated by the buck reaching the pressing position for moving said head toward the buck to press the work.

6. An ironing machine including in combination a pressing head, a pressing buck and a pivotal support therefor, the buck being movable to and fro about its support into inclined position in pressing relation with said head and into inclined work-receiving position in front of the operator, fluid pressure means for moving the 15 buck in both directions, and controls actuatable by an operator at the work-receiving position for causing said moving means to move the buck in either direction.

7. An ironing machine including in combination a pressing head movable to and from pressing position, a pressing buck movable into an inclined position in pressing relation with said head and movable away from the head and into an oppositely inclined position in front of the 20 operator to receive the work, and means for imparting a short, right-line movement of said head toward the buck to press the work.

8. An ironing machine including in combination a pressing head, a pressing buck, a pivotally mounted support for said buck, the support being movable to one side of the vertical to present the buck in inclined position to cooperate with the pressing head and being movable to the other side of the vertical to present the buck in 25 inclined position before the operator, power means for moving the support in both directions and means for effecting the ironing pressure after the support has reached the pressing position.

9. An ironing machine including in combination an open-front frame, a pressing head mounted in the upper front part of the frame, a pressing buck, and a support therefor extending downwardly therefrom and pivotally mounted near the bottom of the frame, the support and buck being movable outwardly away from the head to a work-receiving position before the operator and reversely movable away from the operator into pressing position, and means brought into operation by the support reaching the pressing position for exerting pressure upon the work between the head and buck.

10. An ironing machine including in combination an open-front frame, a pressing head mounted in the upper front part of the frame, a pressing buck, and an integral support therefor extending downwardly from the buck and pivotally mounted near the bottom of the frame, the support and buck being movable outwardly away from the head past a vertical center to work-receiving position before the operator and reversely movable away from the operator into pressing position, and means for exerting pressure upon the work between the head and buck, fluid pressure means for moving the support in both directions, and foot-operated means at the work-receiving station for controlling said fluid pressure moving means.

11. An ironing machine including in combination two pressing mechanisms, each having a 75

- pressing head and pressing buck, the pressing bucks each being movable to and fro in a vertical, arcuate path between pressing relation with its head and a work-receiving and work-discharging position in front of the operator, fluid pressure means for moving the bucks in both directions, and means for controlling said fluid pressure means to move said bucks simultaneously in reverse directions to present one buck at pressing position and the other buck in front of the operator.
12. An ironing machine including in combination two pressing mechanisms, each having a pressing head and a pressing buck, said bucks being swingable to and fro between pressing relation with their respective heads and a work-receiving and work-discharging position in front of the operator, means including fluid pressure double acting cylinders for moving the bucks in both directions, and valve means for simultaneously supplying fluid pressure to said cylinders to swing said bucks in reverse directions to present one buck at pressing position and the other buck in front of the operator.
13. An ironing machine including in combination two pressing mechanisms, each having a pressing head and a pressing buck, the two mechanisms being arranged transversely to each other, said bucks being arcuately movable to and fro in vertical planes between pressing relation with their respective heads and a work-receiving and work-discharging position in front of the operator, the paths of movement of the two bucks being substantially perpendicular to each other, said bucks when in the said work-receiving and work-discharging position occupying in part the same space, and means located for control by an operator at a single station for moving said bucks in reverse directions to present one buck at pressing position and the other buck in front of the operator.
14. An ironing machine including in combination two pressing mechanisms, arranged substantially perpendicularly to each other, and each having a pressing head and a pressing buck,
- pivotaly mounted supports for said bucks, the supports and bucks being swingable outwardly from the front of the mechanism to a work-receiving and delivering position before the operator and inwardly to a pressing position, said bucks when in their outer positions occupying in part the same space, and means located for control by an operator at a single station for moving said bucks in reverse directions to present one buck at pressing position and the other buck in front of the operator.
15. An ironing machine including in combination a head movable to and from pressing position, and mounted to have only straight-line movement, a buck pivotally mounted to swing in the vertical direction and on a constant radius, and power and control means for moving the head toward the buck to effect the ironing pressure in a radial direction with respect to said pivotal mounting.
16. An ironing machine including in combination a buck for supporting the work, a cooperating presser head, suspending means for said presser head spaced apart along the head and each including a compression spring, a plurality of fluid pressure devices for pressing the head to the work against the action of said springs, and separate connections from said fluid pressure devices for acting on the head adjacent to the spaced apart spring suspending means.
17. An ironing machine including in combination a pressing head, a work carrying buck, means for moving the buck to and fro between a work receiving and discharging position and a pressing position, means for pressing the work between the buck and the head, and a timing device for releasing said ironing pressure, said device comprising a cylinder having a piston, means for moving the piston to one end of the cylinder when the ironing pressure is applied and means permitting leakage of air from said cylinder to permit return movement of the piston and means operated by the return of the piston for releasing the ironing pressure.
